MAIL CHUTE

Lester Howard, Long Island City, N. Y., assignor
to Cutler Mail Chute Co., Rochester, N. Y., a
corporation of New York

Application December 9, 1932, Serial No. 646,511

7 Claims. (Cl. 193—8)

My present invention relates to mail chutes, such as are employed generally to conduct mail matter by gravity through the floors of a building to a collection receptacle below, the construction being sectional with units duplicated between the floors, and it has for its object to provide a simple and compact unit of this character that will be convenient in use and having structural details rendering it easily installed. 10 A further object of the invention is to improve the locking means whereby the removable front panels that are occasionally displaced to gain access to the interior of the chute, when clogged or requiring cleaning, are held against tampering. 15 The improvements are directed in part toward features particularly applicable to the twin chutes that have recently come into use to increase the capacity and afford continuous service through one while the other is out of 20 service for any reason. To these and other ends, the invention resides in certain improvements and combinations of parts, all as will be hereinafter more fully described, the novel features being pointed out in the claims at the end 25 of this specification.

Figure 1 is a plan view of the locking bar. Figure 2 is a front elevation of the locking bar with part broken away.

Figure 3 is a front elevation of a twin chute 30 showing the position of the locking bar.

Figure 4 is a cross section thru the locking bar.

Figure 5 is a sectional plan thru a chute just 35 above the locking bar showing the arrangement of the chute in the bar.

Fig. 6 is a view similar to that shown in Figure 3 of a modified form of the invention showing the side covers and to which modification the succeeding figures also relate.

40 Figure 7 is a view showing one side of the view shown in Figure 6 with the side cover omitted.

Figure 8 is a sectional plan showing the neck and ceiling collars at the upper end of the chute.

45 Figure 9 is a detail showing the manner of connecting the neck and ceiling collars to each other and to the chute.

Figure 10 is a cross section thru the locking bar showing the manner of holding the section of the chute extending upward therefrom.

50 Figure 11 is a detail showing the back of one side of the locking bar.

Figure 12 is a sectional plan thru a portion of the chute showing the side cover and also the central filler piece between two chutes.

55 In the drawings the chute is shown as it would

be made wherein numeral 1 indicates the back of the locking bar, numeral 2 the doors, and numeral 3 a chute.

The locking bar may be made, as shown in Figure 1, with the back 1 formed with a flat piece of material having ends 4 and 5 and a center web 6 extending forward. The ends 4 and 5 have small flanges 7 and 8 projecting inward at their upper edges, as shown in Figure 2, and the web 6 is provided with similar flanges 9 and 10 at the upper edge. It will be noted in Figure 2 that the upper portion of the mail chute extending downward into the locking bar bears against the flanges at the upper edges of the ends and central web and extends into the upper end of the lower portion of the chute which extends downward from the locking bar. The upper end of the downwardly extending portion of the chute rests against the inner surfaces of the ends and center web and the lower end of the upper portion of the chute extends into the lower portion as shown.

Forming the locking bar in this manner with a common web 6 between the two chute sections makes it possible to minimize the space between the two chutes and thereby save at least one inch in the overall width of a twin chute. It will be noted that normally the lock bar or door of a locking bar of a mail chute is hinged at one side and the lock located at the opposite or right-hand side and when placing two chutes together it is necessary to leave sufficient clearance between the chutes to permit the door or bar to open about the hinge. It is therefore a feature of this invention to hinge both of the doors of a locking bar at the outer edges and position the locks at the center, as shown in Figure 2. The doors are shaped as shown and have projecting lugs 11 and 12 at the outer ends and similar lugs 13 and 14 at their inner ends. The lugs 11 and 12 dovetail over the tongues 15 and 16 projecting from the ends 4 and 5 and are pivotally mounted thereon by pins 17 and 18. A tongue, which is similar to the tongues 15 and 16, extends from the center web 6 and is provided with a flange 20 at the outer end over which the doors close. The flange 20 may be provided with outwardly extending pins 21 and 22 that fit in corresponding holes in the ends of the doors to locate the doors as they are closed.

Locks 23 and 24 are mounted in the doors, as shown in Figures 2 and 4, and these doors are provided with a locking bar 25 that may be turned to a position behind the edges of the flange 20 to hold and lock the doors in the

110

closed position. The upper outer corners of the doors are beveled, as indicated by the numeral 26, and openings 27 are provided in the beveled surface to receive mail or the like and it will be noted that mail matter placed thru the openings 27 will pass downward into the chute. A closure 28 may be mounted on the inside of the doors with a hinge 29, as shown in Figure 4, so that it may be moved upward to the position shown in dotted lines to close the mail opening 27 when it is not desired to use the chute. This closure may rest upon projections 30 extending outward from the inner surfaces of the doors when it is desired to open the openings 27. It will be noted that by forming the inner ends of the doors in this manner and hinging both doors at the outer edges of the chutes makes it possible to minimize the amount of space required by the doors.

The upper edges of the doors are provided with inwardly extending flanges 31 having recesses 32 and 33 at their outer ends and it will be noted that the moldings at the edges of the chute will pass thru these recesses, as shown in Figure 5. The molding at each corner is formed by a flat plate 34 with a small flange 35 at the inner end, a plate 36 extending backward from the outer end and then forward forming a section 37 and the end of the section 37 is bent inward and backward forming a recess 38 and from the recess 38 this molding extends inward forming a section 39 that holds the inner side of a glass plate 40 that is held in the molding between the flange 35 and the section 39, as shown. The mail chutes 3, that are held in the locking bar are made with channel shaped members having forwardly extending sides 41 and 42, as shown in Figure 5, and these sides are offset at the points 43 providing recesses 44 for the members 36 and 37 of the moldings and the edges of the sides 41 and 42 extend into the recesses 38 of the moldings. It will be noted that molding of any other type or design may be used and the glass plates and sides of the channel shaped member may be held therein in any manner desired.

As before stated, the unit is erected between the floor and ceiling, resting upon a suitable base 70 containing a suitable short floor chute section within the floor (not shown). Vertical angle irons 71 built into the wall support the chute proper 3 through any desired connecting means and the locking bar frame 1 is fastened to these irons. In view of the succeeding description of details of a manner of supporting the chute section on this frame as well as the removable glass panels in the modified general construction of Figs. 6 to 12, these arrangements have been omitted from the showing of Figs. 1 to 5.

There is a head piece 44 at the top of the chute unit suitably supported on the irons 71, which carries screwed thereto collars 45 to make close and well-appearing joints with the ceiling and 46 to overhang the upper edges of the removable panel.

In the design shown in Figure 6 the upper ends of the chutes are similar to those shown in Figure 3 except that head 44 between the ceiling collar 45 and the neck collar 46 is eliminated and the ceiling collar is slidable over the neck collar, as shown in Figures 8 and 9. In this design the neck collar 46 is attached directly to the side 47 of the chute by nut screws 48 and the ceiling collar 45 is attached to the neck collar by countersunk screws 49. It will be noted

that the chute may be set up with the collar 46 in place and secured suitably to upright 71 and the collar 45 may be adjusted on the collar 46 to compensate for variations in the height of the ceiling so that a snug fit may be obtained. After the collar is in the correct position it may be held by the screws 49. Constructing the collars in this manner makes it possible to hold the neck collar 46 direct to the chute and eliminates the cross bar behind the chutes to which the collars are normally held. These collars also provide a very neat appearance at the upper ends of the chutes.

In this design the moldings at the sides are indicated by the numerals 50 and 51 and the back or channel shaped sections of the chutes by the numerals 52 and 53. The locking bar 2, shown in Figure 6, is similar to that shown in Figure 3 and may be mounted upon the chute with the moldings held therein in a similar manner. The glass forming the upper section of the chute, which is indicated by the numeral 54, rests upon a cross bar 55 positioned inside of the locking bar 2 and rigidly connecting the lower ends of the moldings 50-51. This bar is provided with a seat 56 upon which the lower end of the glass rests and in the underside of the bar is a groove 57 which fits over the upper edge of a plate 58 consisting of a sheet metal strip similarly rigidly connecting the side walls 47 of the chute channel at their lower ends, the upper edge of which plate is folded over and thereby reinforced, as shown in Figure 10. In that figure, the lower end fragment of an upper chute section that appears is given the numeral 52 and the connecting section that meets it from below in a joint within the box-like housing member 2 is indicated at 52a. Element 58 is on the lower end of 52. Forming this member in this manner eliminates the special complicated cross bar that is normally used and thereby provides a much more economic construction. At the back of the upper chute section 52 is a clip 59 opposite to plate 58 which fits over the narrow section 60 of the back of the locking bar, as shown in Figures 10 and 11. This clip may be attached to the back of the chute by any means and it will be noted that as the chute is placed in the locking bar this clip will pass over the portion 60 of the bar and throw the back of the chute snugly against the back of the bar so that the back of the chute will be rigidly held in place.

In the cross section shown in Figure 12 there is a small space 61 between the two chutes and this is filled by a central filler piece 62 which may be in the shape of a channel, as shown, and one edge of which may be held under a clip 63 that may be attached to the end wall 64 of the chute 53, as shown. It will be understood that the clip 63 may be placed on either chute and also that any number of the clips may be used and these may be placed on either or both chutes, as may be desired. It will be noted that this member 62 completely closes the front of the opening 61 and will, therefore, provide a very neat appearance.

In this design the moldings 51 and 52 are formed with flat square surfaces and these are provided with flanges 65 that fit into recesses 66 in the ends of the chutes. The glass may be held in the molding as shown.

At the sides of the chutes are covers 67 and 68 which are formed as shown in Figure 12 and it is preferred to make the exposed surfaces of

these covers black whereas the moldings are chromium plated so that a very attractive chute is provided and this has a black border. These chute covers at the sides may be of any shape or design and may be arranged in any manner.

It will be understood that other changes may be made in the chutes without departing from the spirit of the invention one of which changes may be in the general design of the front of 10 the bar as it will be understood that this may be made ornamental instead of plain, as shown. Another may be in the use of other means for hinging and locating the doors to the bar, another may be in the use of other means for 15 mounting the chute sections in the bar, and still another may be in the arrangement of the letter slots in the doors of the bar as it will be understood that these may be located in any position and arranged in any desired manner. It will 20 also be understood that other changes may be made in the details of construction of the chute parts and these may be formed and arranged in any manner desired.

The construction will be readily understood 25 from the foregoing description. In use the chute may be provided as shown and the words U. S. Mail placed on the front of the doors or front plates of the locking bar and the chute sections may be arranged in the bars as shown and described. By forming the locking bar in one piece 30 or one casting, arranging the central member as shown and described, hinging and locating the doors as shown and described, and offsetting the inner edges of the chute channels to provide 35 space for the molding flanges, makes it possible to reduce the overall width of a twin chute or of two chutes in combination so that the minimum amount of space is required. It will be noted that either of the doors may be unlocked 40 and opened and the glass sections removed when it is desired to examine the chute or remove mail that may be caught therein, and the particular arrangement of the locks and hinges makes it possible to mount the doors in the 45 space required for the locking bars even if the hinges and locks were not used.

Having thus fully described the invention, what I claim as new and desire to secure by Letters Patent, is:

50 1. In a mail chute locking bar, a back formed of one continuous piece with projecting flanges at the center and ends, doors hinged to the end flanges, and means for locking the doors at the center.

55

60

65

70

75

2. In a mail chute locking bar, a continuous one piece back having a web extending forward from the center and flanges extending forward at the ends, front plates hinged to the ends of the end flanges, said front plates having letter slots therein, and means locking the ends of the front plates at the center.

3. In a locking bar for mail chutes, a bar having a continuous back extending across two chutes, a flange at the center extending between the chutes, flanges at the ends, front plates hinged to the flanges at the ends, and means locking the front plates to the flanges at the center.

4. In combination, a continuous one piece locking bar for two mail chutes, bars hinged to the outer ends of the bar, means for locking the said hinged bars at the center of the said continuous one piece bar, mail chutes adapted to be held in the said bar, glass plates at the front of the said chutes, moldings adapted to hold said glass plates, and recesses in the sides of said chutes permitting space for said moldings.

5. In a mail chute, the combination with a supporting frame constituting a housing and upper and lower chute sections jointed together within the housing, the upper section embodying a channel having an open front and a supporting plate bridging the lower end thereof within the housing, of a removable panel for said upper chute section having a transverse bar at its lower end seated upon the plate.

6. In a mail chute, the combination with a fixed upright wall support and a vertical chute section carried thereby and embodying a channel member and a panel closing the front thereof, said panel consisting of moldings cooperating with the side walls of the channel in a separable joint, of cover plates extending forwardly from the upright support in spaced relation to the side walls of the channel and cooperating with the moldings to conceal the said joints.

7. In a mail chute, the combination with a support, a locking bar frame carried thereby and twin chute sections extending into said frame side by side and provided with removable front panels, of a pair of locking bars hinged to opposite sides of the frame and of the chute sections and having their free ends meeting between the two and provided with key controlled locks.

LESTER HOWARD.
